United States Patent

Des. 240,386
Patented July 6, 1976

240,386

COFFEE MAKER

Franz Alban Stuetzer, Muehlheim, am Main, Germany,
assignor to Rowenta-Werke, GmbH, Offenbach am
Main, Germany

Filed July 26, 1974, Ser. No. 492,124

Claims priority, application Germany Jan. 29, 1974

Term of patent 14 years

Int. Cl. D7—02

U.S. Cl. D7—62

FIG. 1 is a perspective view of a coffeemaker showing my new design;

FIG. 2 is a side elevational view of the side not shown in FIG. 1;

FIG. 3 is an end view taken from the reservoir vessel end;

FIG. 4 is an end view taken from the brewing vessel end; and

FIG. 5 is a top plan view thereof.

The bottom of the coffeemaker is unornamented.

I claim:

The ornamental design for a coffeemaker, as shown and described.
